(57) **CLAIM**

The ornamental design for a video processing unit for a visual prosthesis, as shown and described.

DESCRIPTION

FIG. 1 is a top right perspective view of the video processing unit.

FIG. 2 is a front view of the video processing unit.

FIG. 3 is a rear view of the video processing unit.

FIG. 4 is a right side view of the video processing unit.

FIG. 5 is a left side view of the video processing unit.

FIG. 6 is a top view of the video processing unit; and,

FIG. 7 is a bottom view of the video processing unit.

1 Claim, 6 Drawing Sheets

FIG. 1

FIG. 2

FIG. 3

FIG. 4

FIG. 5

FIG. 6
